FLOATING ROOF LIQUID STORAGE TANK STRUCTURE

Henry Grundig, Elizabeth, N. J., assignor to Esso Research and Engineering Company, a corporation of Delaware

Application December 14, 1954, Serial No. 475,226

10

7 Claims. (Cl. 220—26)

The present invention relates to the construction of storage tanks. More particularly, the invention relates to storage tanks wherein the liquid contents are covered by means of a floating roof which is buoyantly supported in the tank on the surface of the liquid contents, and including conduit means for the withdrawal and introduction of liquids from and into the tank.

In the art of tank construction, a prime factor is the provision of a storage tank with facilities for substantially complete withdrawal of the contents by way of the conventional conduits provided, in order to avoid the condition wherein once the storage tank is filled, a substantially perpetual "bottom inventory" is maintained. In most forms of construction, a single conduit connection is provided for the introduction and withdrawal of liquids. In such tanks, the conduit connection may be located from two to three feet, or more, above the bottom of the tank. This is especially true in floating roof tanks, where a depth of at least three feet of liquid is ordinarily retained in the tank in order to maintain the roof in surface contact with the liquid at all times, and to avoid blocking of the conduit connection orifice by the roof structure.

It is an object of the present invention to provide a liquid transfer, conduit connection for a storage tank, and particularly for a tank which is equipped with a floating roof, and wherein such connection is made substantially at the tank bottom. It is also an object of this invention to accomplish such connection in cooperation with related means whereby bottom sediment, sludge, or water is prevented from entering the orifice, and whereby a floating roof may be employed without interference with flow into or from the proposed conduit connection.

The invention may be more fully understood from the following description when it is read in conjunction with the accompanying drawings, in which:

Fig. 1 is a view in vertical section through a side wall and bottom portion of a typical storage tank equipped with a floating roof, and including in the view a peripheral edge portion of the roof as well as a transfer line conduit connection to the tank according to the present invention;

Fig. 2 is a view in vertical section at right angles to that of Fig. 1 taken along a line II—II thereof, and in which the conduit connection is indicated by dotted lines;

Figs. 3, 4 and 5, each is a view of a portion of the under surface of the storage tank roof of Fig. 1 taken from below and vertically upward illustrating the conformation of the edge portions of three specific forms of the channelled course illustrated in vertical section by Fig. 1 and in end elevation by Fig. 2.

Referring to the drawings in greater detail, the numeral 1 designates the side wall of a storage tank, and the numeral 2 the bottom wall thereof. As shown, the tank is provided with a conduit connection means such as the tubular nozzle 3 which opens through a receiving orifice

5

2

4 in the side wall of the tank at substantially the level of the bottom wall 2. A facing or reinforcing plate 5, and a bottom extension and reinforcing plate 6 are provided at the orifice. The nozzle 3, and plates 5 and 6 are joined as by welding in substantially integral, fixed and fluid-tight relation to each other and to the bottom and wall of the tank. When so installed, the axis of the nozzle 3 is spaced above the bottom wall 2 at a distance substantially equal to the nozzle radius. Internally of the tank is an elongated plate 7, which is secured at its end edges in fluid-tight relation to the tank wall at either side of the orifice, and similarly at its lower longitudinal edge to the tank bottom. The plate 7 thus forms a dam or weir which provides a laterally enclosed area in the vicinity of the orifice 4. The plate 7 has a lateral dimension not more than the diameter of the orifice 4, minus four inches, but, preferably not substantially less than twelve inches. The length of the plate, while it may vary slightly, is preferably such that the opposite ends may be attached to the tank wall at opposite sides of the nozzle orifice 4 in spaced relation thereto at a distance substantially equal to the diameter of the orifice, and such that when thus attached, the mid point of the longitudinal axis of the plate 7 may be located so as to be spaced from the orifice and the tank wall at a distance of about twice the diameter of the orifice.

The tank structure illustrated, includes a floating roof. The floating roof employed may be either a pan type, or a pontoon type, or a double-deck type. The pan type has a deck of single thickness and an upstanding rim at the outer edge. The pontoon type has an annular closed pontoon with a circular center deck covering the area enclosed by the pontoon. The double deck type is similar to the pontoon type with an upper deck joined at its peripheral edge to the upper edge of the rim, and supported in vertically spaced relation to the lower deck. The portion of the roof shown in the drawings is typical of the peripheral edge of either the pontoon type or the double-deck type of floating roof contemplated.

In the drawings, the numeral 11 designates a lower deck portion of a double deck floating roof, the numeral 12 the upper deck, and the numeral 13 the rim portion which has upper and lower edge portions 14 and 15, respectively. In such a roof, the rim is substantially vertical, and parallel to the tank wall; the lower deck is sloped radially downward from the vertical axis of the roof to a juncture with the lower edge of the rim; and the upper deck is sloped radially upward from the vertical axis of the roof to a juncture with the upper edge of the rim. The diameter of the roof at the rim is less than that of the interior diameter of the tank providing for a radially spaced relationship therebetween.

The radially spaced relationship of the roof to the tank is maintained and the roof is substantially centered in the tank by means substantially as shown. Such means, shown in the drawings, include a vertical seal ring 16 resiliently supported by the floating roof at the rim thereof by any suitable means, such as indicated by the numeral 17, and an annular closure 18 for the upper end of the annular space between the ring 16 and rim 13. The support means 17 is shown as a pair of interlocked spring elements pivoted at their connections to each other, and to the ring 16 and rim 13, but any other means serving the purpose of supporting the ring 16 and forcing it into reciprocally slidabile, surface contact with the inner surface of the tank wall would be suitable. The annular closure 18 is preferably formed of a flexible, deformable, fluid-tight material such as a woven material impregnated with a plastic or rubber-like substance. Neoprene impregnated asbestos cloth is an example of such a material. This closure has a width greater than the annular space to be maintained between

55

70

the rim 13 and the tank wall or the seal ring 16 and may be held in fluid-tight sealing relation to the ring and rim as by means of annular clamps secured to each and designated in the drawings by the numerals 19 and 20. Any conventional means to prevent rotation of the roof may be provided. Also, as in the conventional floating roof structure, the roof as shown in the drawings is provided with means for supporting the roof in vertically spaced relation to the tank bottom, when the contents may be reduced to less than the volume of liquid displaced by the roof. Such support means ordinarily consist of a plurality of tubular members extended through the upper and lower surfaces of the roof and each adapted to receive a support leg which may be extended from or withdrawn into the lower end of a tubular member. A typical support means is generally illustrated in the drawings wherein the tubular member is designated by the numeral 21 and the extension leg by the numeral 22. Reinforcing plate 23, secured to the tank bottom, is provided to receive the lower end of the leg 22. The support means as now contemplated, however, differ from those conventionally employed. Whereas in the conventional structure these supports are designed to hold the roof at a level such that the rim is from three to four feet above the tank bottom, according to the present invention, at its lowermost level the roof is supported with the rim at a distance above the tank bottom which is about four inches less than the diameter of the nozzle 3 and orifice 4, although preferably not less than twelve inches above the tank bottom.

As a feature of the roof construction according to the present invention the rim 13 in the area of juxtaposition to the nozzle 3 and orifice 4 is provided with an arcuate notch portion as indicated by the numeral 31, while the adjoining lower deck portion 11 of the floating roof is provided with an arcuately indented portion 32 forming a channelled course extending radially inward from the rim notch 31. As shown, this indented portion 32 has an initial radius of curvature at the rim substantially equal to that of the notch portion 31, both having a radius substantially greater than that of the nozzle 3. Also as shown, the channelled course 32 has the general form of the surface of the smaller of two conical portions divided by the intersection of a plane with a right circular cone, from the apex thereof to a chord in the base which chord is equal to or less than the diameter of the base. Other conic forms or shapes also may be utilized in producing the indented portion 32, but preferably the edge portions, designated in the drawings by the numerals 32a and 32b thereof will be substantially congruent with those of a conic section of a circular cone wherein the radius of the base of the cone is substantially equal to the radius of curvature of the rim notch portion 31, and wherein the arcuate measure of the rim notch portion is not substantially more than 180°. The specific relationships contemplated would provide a rim notch portion 31 constituting a circular segment having a rise such that with the roof fully depressed the apogee of the segment arc will be spaced from the tank floor by a vertical distance at least equal to the diameter of the nozzle 3, and in any event so that the distance will not be less than the greatest vertical distance between the tank floor and the circumference of orifice 4. The width of the segment, that is the straight line distance between the opening of the notch should be somewhat greater than the diameter of the nozzle or orifice and preferably slightly less than the width of the area enclosed by the weir 7.

The conic forms or shapes contemplated by the relationships as set forth above have been represented in Figs. 3, 4 and 5. In these figures, like parts have been designated by the same numerals. As shown, Fig. 3 represents the conformation of the edge portions 32a and 32b of the channelled course which is also specifically illustrated by Figs. 1 and 2, and wherein the cor-

responding conic section is formed by a plane which cuts the cone from the apex thereof through a chord in the base thereof. Such a conic section has a generally triangular form and the curve of intersection is two intersecting straight lines meeting at the apex designated by the numeral 32c. In the form represented by Fig. 4, the edge portions 32a and 32b correspond to those of a conic section formed by a plane which cuts through the cone in parallel relation to a plane tangent to the surface of such cone, and wherein the curve of intersection is a parabola. The third form, shown by Fig. 5, has edge portions 32a and 32b which correspond to those of a conic section formed by a plane which cuts through the cone in non-parallel, angular relation to a plane tangent to the surface of the cone, and wherein the curve of intersection is a hyperbola.

In addition, the sealing ring 16 also is provided with a notch portion 33 which extends upwardly from the lower edge of the ring to a depth greater than the depth 20 of the notch portion 31 in the tank roof rim 13. The notch portion 33 as shown is disposed in opposed and aligned relation to the nozzle and rim notch portion 31. This notch portion should have a dimension at the opening adequate to receive the upper edge of the weir freely, 25 and should have a depth such that when the roof is depressed the greatest vertical distance between the uppermost level of the notch portion and the tank floor is not less than the greatest vertical distance between the tank floor and the circumference of the orifice 4.

30 When constructed in the foregoing manner, the roof supports may be positioned so as to permit withdrawal of liquid therefrom to a depth substantially below the upper level of the inlet-outlet nozzle 3 and orifice 4, while maintaining surface contact of the roof with the residual 35 liquid inventory, and without substantially reducing or interfering with flow into or from the tank through the nozzle 3. In the apparatus as described, the dam or weir 7 substantially prevents the entrance of undesired sludge or residual liquid into the nozzle 3. The notched portions 40 31 and 33 avoid flow restriction of the nozzle by either the seal ring 16 or the roof rim 13. The indented portion 32, as described and shown, provides for substantially free communication between the nozzle 3 and the tank beyond the dam 7. By permitting the floating roof to descend 45 to a lower level than possible with conventional structures, the apparatus as described permits withdrawal of greater quantities of liquid from the tank without producing a vapor space between the roof and the remaining liquid contents. In the storage of volatile and inflammable liquids, by this means not only are evaporation losses substantially reduced, but also in eliminating a vapor space above the liquid the hazards of fire and explosion 50 are substantially minimized. In addition, by reducing the required minimum tank inventory, a greater working capacity is obtained. The increased working capacity in gallons which is obtained for each foot of reduction in residual tank inventory is equal to $7.48957 \pi r^2$. Thus in a tank having a diameter of 150 feet, a two foot reduction in residual inventory is equal to an increase in working 55 capacity of the tank of more than 264,000 gallons.

As a specific example of a tank and floating roof structure according to the present invention, a tank having a diameter of 150 feet and a height of about 48 feet would be provided with a floating roof having a diameter of 60 about 148 feet, 10 inches. When centered, this roof would be spaced radially from the tank wall by a distance of about 7 inches. In a typical roof of such diameter the rim (13) would have a vertical dimension of about 3 feet, 5 inches, extending above the upper deck (12) of the roof structure by a distance of about 2 inches to provide for attachment along one edge of a flexible annular closure element (18), the other edge of the closure being attached to the upper edge of an annular seal ring or shoe (16). The annular shoe would have a vertical dimension of about 3 feet, 11½ inches, and would be sup-

ported to extend above the upper deck by a distance of about 6 inches, and below the lower deck (11) by a distance of about 2½ inches.

A conventional tank structure of this character, would be provided with an inlet or outlet orifice (4) and nozzle (3) about 20 inches in diameter. As compared with this conventional arrangement in the structure according to the present invention the axis of the inlet or outlet orifice nozzle would be spaced from the tank bottom at a distance substantially equal to the radius of the nozzle, namely ten inches above the bottom. As previously indicated a dam or weir member (7) is provided to enclose an area in the immediate vicinity of the nozzle and orifice. In the tank contemplated this dam would be about sixteen inches high, the ends being secured to the tank wall on each side of the orifice at a distance from the orifice of about twenty inches and the midpoint of the dam would be spaced from the orifice, radially of the tank at a distance of about forty inches. The supports (22), provided to hold the roof above the tank bottom when the contents are reduced to less than the volume displaced by the roof, in the present structure contemplated would be arranged to provide a distance of about sixteen inches between the rim (13) and the bottom wall (2) of the tank. Also, in the roof structure contemplated by the present invention the indented portion (32) provided in the lower deck of the roof, opens through a notch portion (31) in the rim of the roof wherein the notch portion has a radius of curvature of about twenty inches, and an opening width at the rim edge having a straight line distance between the edges of about forty inches. The uppermost point in the notch portion would be about twenty inches above the tank floor with the roof fully depressed.

The indented portion (32) would have initial dimensions identical with those of the notch portion (31), and at a distance from the outer wall of the tank equal to that of the midpoint of the plate forming the weir (7), a radius of curvature of about ten inches. Likewise in this specific example, the seal ring notch portion (33) would have a radius of curvature such that the circular segment formed would provide a straight line distance between the lower edges of the notch opening equal to about sixty inches. The uppermost point in the notch portion would be about twenty inches above the tank floor with the roof in a fully depressed position.

What is claimed is:

1. In a storage tank, including a bottom wall, a cylindrical upright wall extending upwardly from said bottom wall, a conduit connection nozzle opening into said tank through said upright wall immediately adjacent said bottom wall, a floating roof in said tank, including a floor and a vertical peripheral rim portion, said roof adapted to be supported primarily on the surface of a liquid contained in said tank, and thereon to be positioned at various levels within the tank as said liquid is introduced and withdrawn, said roof also including rigid support means extended downwardly from said floor adapted to establish a lower most position for said roof at a level which is below a horizontal plane tangent to said nozzle and in vertically spaced relation to the tank

bottom wall, a vertical sealing ring resiliently supported on said roof rim in substantially parallel radially spaced relation thereto and in substantially fluid tight surface contact with the inner surface of the tank wall, an arcuate notch portion extending upwardly in said ring, an arcuate notch portion extending upwardly in said rim, and a channelled course defined in the roof floor opening downwardly therefrom, said channelled course extending radially inward from said rim and coincident at its outer end with said rim notch portion, each of said sealing ring and rim notch portions having a radius of curvature greater than that of said nozzle and disposed in opposite alignment with said nozzle radially of said tank and roof.

2. An apparatus according to claim 1 wherein said arcuate, roof rim, notch portion is substantially a segment of a circle, wherein the surface of said channelled course substantially corresponds to that of the smaller of two cone portions formed by the intersection of a plane with a right circular cone having a base radius equal to that of said rim notch portion, the intersection of said plane with said cone extending through the base of said cone along a chord thereof, and wherein the lateral edge portions of said channelled course substantially correspond to the curve of intersection of said plane with said cone.

3. An apparatus according to claim 2 wherein said curve of intersection of said plane with said cone is two intersecting straight lines.

4. An apparatus according to claim 2 wherein said curve of intersection of said plane with said cone is a parabola.

5. An apparatus according to claim 2 wherein said curve of intersection of said plane with said cone is a hyperbola.

35 6. An apparatus according to claim 1, including an elongated plate having a lateral dimension at least equal to the radius of said nozzle, wherein said plate is secured to the bottom wall of said tank, extending vertically upward therefrom, and wherein said plate is secured at each end to the upright wall of said tank in opposed relation diametrically of said nozzle and radially spaced therefrom, said plate forming a weir enclosing an area of the tank bottom wall extending inwardly from the opening of said nozzle through the upright wall, and also wherein the straight line distance between the intersection of said sealing ring notch portion with the lower edge of said ring is greater than the lateral dimension of the area enclosed by said elongated plate vertically below said notch portion.

40 7. An apparatus according to claim 6, wherein said channelled course extends radially inward of said tank roof bottom to a distance substantially greater than the inward extension of the area of said tank bottom wall which is enclosed by said elongated plate.

55 8. An apparatus according to claim 6, wherein said channelled course extends radially inward of said tank roof bottom to a distance substantially greater than the inward extension of the area of said tank bottom wall which is enclosed by said elongated plate.
